CIGARETTE ROD FORMER

Wilhelm B. Bronander, Montclair, N. J., assignor
to American Machine & Foundry Company, a
corporation of New Jersey

Application June 1, 1936, Serial No. 82,845

5 Claims. (Cl. 131—66)

This invention relates to cigarette rod forming mechanism and particularly to a mechanism for vibrating or imparting to and fro motion to parts confining or forming the tobacco stream which forms the rod, as for instance the tongue or other rod-forming part, in such a manner as to facilitate the making of more uniform cigarettes at high speed.

10 In operating cigarette machines at high speed, the work of the tongue and other parts in compressing or confining the moving stream of tobacco approximately to rod size, as the cigarette wrapper is folded about the rod, has been increased, and increased lack of uniformity of cigarettes made at high speed is attributed to hesitation or temporary holding up of the tobacco stream at these parts, as for instance at the small end of the tongue where compression is frequently greatest.

15 Also, at high speed, much trouble resulted from breaking of the rod, believed due to choking at the tongue as the rapidly moving stream of tobacco passes under and is compressed by the stationary surface of the tongue.

20 The main object of the invention is to eliminate or minimize the above difficulties by vibrating or moving the tongue or other rod confining parts. In this connection, it is my aim to produce a movement of the tongue which will actually aid in forwarding the tobacco, even at the point of greatest compression, instead of resisting the movement of the tobacco by pressure of a stationary surface thereon as hitherto.

25 Still another object is to move the tongue toward and away from the tobacco stream so as to produce a vibratory effect which will tend to release or unblock almost immediately any chokes which might break the rod, or any partial chokes which might cause holes or soft places in the cigarettes or so-called "broken neck" cigarettes.

30 To these ends, means is provided for imparting to and fro vibratory motion to the former tongue or other rod confining parts, toward and away from the tobacco stream which forms the rod. Also means is provided for giving a motion of the tongue along the tobacco stream. While it is not necessary that the two motions be combined, the best results follow from such combination, such for instance as results from a diagonal motion to and along the stream in the direction of its movement, or a movement to, along, away from and back relative to the stream.

With these and other objects not specifically mentioned in view, the combination consists in certain constructions and combinations herein-after fully described and then specifically set forth in the claims hereunto appended.

5 In the accompanying drawing in which like characters of reference indicate the same or like parts:

Fig. 1 is a front elevation, partly in section, of the improved cigarette rod former; 10

Fig. 2 is a sectional end elevation taken on line 2—2 of Fig. 1;

Fig. 3 is a section end elevation showing the tongue in connection with the motor shaft;

Fig. 4 is a partial front elevation of a modified 15 form of Fig. 1;

Fig. 5 is an end view of the same; and

Fig. 6 is a detail view of a section of a modified form of tongue.

20 Referring now to the drawing, in the form selected to illustrate the invention a motor shaft 10 of motor 11, Fig. 1, has an eccentric shoulder 12 which engages in the bearing 13 integral with tongue 14. The small end of said tongue is provided with a holder 15 which receives one 25 end of a flat spring 16, the other end of spring 16 being attached to a stationary member 17 of the cigarette machine. The flat spring limits the tongue to a motion in the plane of the tongue.

30 The narrow stream of tobacco T for forming the cigarette rod is forwarded by an endless tape 18 guided in a bottom plate 19, which as seen in Fig. 3, is provided with a hollowed out portion which gradually terminates in a semi-circular opening, as shown in Fig. 2, which causes the tape 18 to fold the paper P around the tobacco T.

35 The motion imparted to the tongue by the eccentric permits the tongue to iron or level out any irregularities in the stream of tobacco and even more important tends to relieve almost instantaneously any momentary tendency of the tobacco to choke or hesitate as it passes under the tongue, especially the small end thereof. The 40 spring 16 is so placed that it holds the end of the tongue from resting on the traveling paper strip "P".

45 Referring to Figs. 4 and 5, in the modification therein illustrated, the small end of tongue 14 is provided with a guide 15a which engages in a slotted lug 20 carried by guide bars 21 of bottom plate 19. The tongue is also provided with a member 22 carrying an adjusting screw 50

23 which rests against the bar 21, said screw providing means for holding the tongue from falling upon the traveling paper strip P.

Referring to Fig. 6, the tongue 14 is shown 5 with a stepped surface 14a which provides a more positive feeding effect.

It is noted that an independent motor is provided which may be operated at speeds far in excess of that of the cigarette machines, such 10 as 6,000 or more revolutions per minute.

While the invention has been described in connection with the rod forming tongue, it is contemplated that the invention be applied to other parts acting to form or confine the rod 15 for the purpose of forming a more uniform rod and minimizing friction and choking. The invention is particularly applicable to compressing or confining parts overlying or engaging the sides or bottom of the rod intermediate the tobacco feed and the actual closing of the rod. 20

It is noted that the flat spring 16 extends diagonally somewhat rearwardly so that it is at an acute angle to the direction of movement of the stream of tobacco. Thus the forward end of 25 the tongue has a diagonal movement forwardly and somewhat downwardly and a rearward movement which is somewhat in an upward direction. Thus, there is a greater compression or rubbing action of the tongue on the tobacco during 30 the forward movement of the tongue and this compression or friction is relieved during the rearward movement of the tongue.

It is contemplated that the motor will be operated at such speeds as to produce linear movement of the tongue or other tobacco stream-engaging element at a speed greater than the linear speed of the stream, so that the tongue or other 35 stream-engaging element tends to push the tobacco forwardly at greater than rod speed, resulting in a longitudinal compacting or compressing of the rod tending to fill any holes or spots of low density. In this connection the barbed or serrated surface shown in Fig. 6 serves to provide a more positive forwarding and compacting 40 action.

45 What is claimed is:

1. In a cigarette machine, the combination with means for advancing a web of cigarette paper, to inclose, in progressively tapering formation carried by the web, a stream of tobacco, of a cigarette-forming tongue of progressively tapered arcuate cross-section, overlying said paper and engaging said tobacco, and means for vi-

brating said tongue relatively to said stream of tobacco.

2. In a cigarette machine, the combination with means for advancing a web of cigarette paper with a stream of tobacco thereon, of a cigarette rod forming tongue overlying said paper and engaging said tobacco, a resilient member supporting one end of said tongue, and means for vibrating said tongue, said means including a rotating eccentric and means connected to the other end of said tongue engaging said eccentric. 10

3. In a cigarette machine, the combination with means for forwarding a narrow stream of tobacco having a cross-section approximating that of the cigarette rod for forming a cigarette 15 rod, of an element having a surface extending along and engaging said stream, and means giving said element to and fro movement having a component of motion in the direction of movement of the stream at a linear speed greater than that of the stream to produce an axial compression on the stream while forwarding the same. 20

4. In a cigarette machine, the combination with means for forwarding a narrow stream of tobacco having a cross-section approximating that of the cigarette rod for forming a cigarette rod, of an element having a surface extending along and engaging said stream, and means giving said element to and fro movement having a component of motion in the direction of movement of the stream at a linear speed greater than that of the stream to produce an axial compression on the stream while forwarding the same, said element having forwardly directed 25 barbs or teeth arranged to feed the stream forwardly on forward movement of the element while permitting relative movement of the element and the stream on backward movement of the element relative to said stream. 30

5. In a cigarette machine, the combination with means for advancing a web of cigarette paper, to inclose, in progressively tapering formation carried by the web, a stream of tobacco, of a cigarette-forming tongue of progressively tapered arcuate cross-section, overlying said 45 paper and engaging said tobacco, and means for vibrating said tongue relatively to said stream of tobacco, said means including mechanism imparting to said tongue a movement having a component of motion in the direction of movement of said stream. 50
